DISPENSER

Kjell Waring, Forest Hills, Long Island, N. Y., assignor of one-third to Olaf I. Waring, Flushing, and one-third to Pincus Rothberg, New York, N. Y.

Application June 25, 1942, Serial No. 448,406

15 Claims. (Cl. 206—42)

This invention relates to dispensers. It is directed to the provision of containers for pills, tablets, capsules and other small articles, having means for facilitating the dispensing or removal of one or a few of such articles for use.

The inconveniences in the use of receptacles, such as bottles, tins, boxes, or other containers filled with tablets or other small articles are only too well known. In general, the bottle or jar is overturned and the user attempts to shake out one or more of the articles, with the result that some fall to the ground, or more than necessary are shaken out.

It is the object of my invention to provide a container having means whereby the contents may be easily dispensed by separating one or more of the tablets, capsules or the like articles in a simple overturning movement of the container which causes one or more of the articles to become separated from the mass and become accessible while still in the container or in the cover for removal by hand one or more at a time. This effects saving of material and time and enables easy and ready removal or dispensing of the articles.

A further object of my invention is to provide a container wherein said saving of time and material and ease of operation are accomplished by a very simple and inexpensive device which should not materially increase the cost of the present day containers.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the claims.

In the accompanying drawing, in which are shown various possible embodiments of my invention, and in which like numerals refer to like parts throughout,

Fig. 1 is an elevational view in partial section of a bottle embodying my invention;

Fig. 2 is a bottom plan view of the bottle cap shown in Fig. 1;

Fig. 3 is a sectional view through a bottle cap embodying a modified form of my invention;

Fig. 4 is a view similar to Fig. 1 of a bottle embodying another modified form of my invention;

Fig. 5 is a view similar to Fig. 1 of a bottle embodying still another modified form of my invention; and

Fig. 6 is a top plan view of the bottle shown in Fig. 5 with the cap removed.

In general, I accomplish the foregoing objects of my invention by providing on the inside surface of the container or in the interior of the cover or closure a member to which the articles in the container can easily and readily be lightly attached by manipulation of the container. This member may comprise a sticky area, so located that when the container is in normal vertical position, such area will be above the level of the articles, so that it is easily accessible. Thus, this sticky area may be provided on the interior of the cover or on the inner surface of the container near the opening. When the container is inverted, one or more of the articles, depending upon the relative size of the same and of the adhesive area, will adhere to the latter. When the container is righted, the adhered articles will separate from the mass and will dangle from said area, the adherence being so slight that the separated articles may be readily detached. The size of the sticky area may be chosen so that approximately a predetermined number of the articles may be dispensed at each operation. Thus, each operation may dispense a prescribed dosage in the case of pharmaceutical or medicinal products.

Referring now to the drawing and more particularly to Figs. 1 and 2, I have there shown a container 10 embodying one form of my invention. Said container is in the form of a glass bottle 12, the contents of which may comprise one-piece pharmaceutical capsules or pills 14. The mouth 16 of the bottle is closed off by a cap 18 which is detachably secured to the bottle, as by cooperating threads 20 on the cap rim 22, and threads 24 on the bottle neck 26. A liner 28, underneath the crown 20 of the cap, is provided in any suitable manner, as by punching, with a central aperture 32 at least large enough to permit a capsule 14 to project partially therethrough. Superimposed on said liner is a layer 34 of material to which has been applied an adhesive coating 36. In this manner, the layer 34 will adhere to the back of the liner 28 and a sticky area 38 will be exposed on the under surface of the cap.

In Fig. 3 I have shown another form of my invention, wherein a sticky coating 40, instead of being applied to a layer of material sandwiched between the crown and liner, is applied directly to the inner surface of the crown. A portion 42 of this coating is exposed through the aperture 32 in the liner 28 to provide the desired sticky area.

Still another form of my invention is illustrated in Fig. 4. The cap 18 of the container 10 has an unperforated liner 44 underlying the crown 30. An exposed central area of said liner has an adhesive coating 46 applied thereto to provide a sticky area to which two-piece capsules 48 may adhere.

Figs. 5 and 6 illustrate another modification, wherein the container 50 includes a glass jar 52 whose mouth 54 is wide enough to easily permit insertion of one or more fingers. The plastic cap 56 and liner 58 are conventional. However, on the inner surface of the jar 52 near the mouth 54 there is provided a coating of sticky material 60 which forms the desired sticky area.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. A package comprising a container having a mass of small articles housed therein, said container including a receptacle having an open mouth and a cover for opening and closing said mouth, said container mouth being so small that said articles are inaccessible for removal by hand when the receptacle is upright and the receptacle cover is in open position, and an area of sticky material supported by and within said container, said area being positioned to be manually accessible when the cover is in open position, clear of the mass when the container is upright, and accessible to any article in the mass without movement of the area relative to the receptacle when the container is inverted with its cover closed so that when said container is turned upside down with its cover closed a random article will adhere to said area and separate from said mass upon reversion of said container whereupon it is accessible for removal by hand when the cover is opened.

2. A package as set forth in claim 1 wherein the area is inside of the container and adjacent the mouth of the receptacle.

3. A package as set forth in claim 1 wherein the area is on the interior of the container and adjacent the mouth of the receptacle.

4. A package as set forth in claim 1 wherein

the area is carried by the cover on the interior of said container adjacent the mouth of the receptacle.

5. A package as set forth in claim 1 wherein the area is carried by the receptacle on the interior of the container adjacent the mouth of the receptacle.

6. A package as set forth in claim 1 wherein the area is on the inside surface of the receptacle adjacent the mouth thereof.

7. A package as set forth in claim 1 wherein the area is over the mass of articles when the container is upright.

8. A package as set forth in claim 1 wherein the area is on the inside surface of the cover.

9. A package as set forth in claim 1 wherein the area is on the inside surface of the cover and is smaller than said surface.

10. A package as set forth in claim 1 wherein the least dimension of the area is at least equal to the least dimension of the articles.

11. A package as set forth in claim 1 wherein the area is on the inside surface of the cover, is smaller than the surface and is spaced from the periphery thereof.

12. A package as set forth in claim 1 wherein a liner is provided inside of the cover and exposed to the interior of the container and the area of sticky material is supported on the surface of said liner facing the inside of said container.

13. A package as set forth in claim 1 wherein a liner is provided on the inside of the cover and is exposed to the interior of the container and the area of sticky material is associated with said liner in such manner as to also be exposed on the inside of said cover, said area being smaller than said liner and being spaced from the periphery thereof.

14. A package as set forth in claim 1 wherein a liner is provided on the inside of the cover and is exposed to the interior of the container, said liner having an aperture, a layer of material intermediate of said liner and the crown of the cover and in juxtaposition with said liner, said layer lying across said aperture, the area of stick material being on the surface of said layer next to said liner.

15. A package as set forth in claim 1 wherein a liner is provided on the inside of the cover and is exposed to the interior of the container and the area of sticky material covers at least a portion of the inside exposed surface of said liner.
